TELEPHONE SET FOR COMMUNICATION IN
AIRPLANES

Karl Wenzky, Berlin, Germany, assignor to
Siemens Apparate und Maschinen Gesellschaft
mit beschränkter Haftung, Berlin, Germany, a
corporation of Germany

Application September 9, 1937, Serial No. 163,077
In Germany September 7, 1936

4 Claims. (Cl. 179—156)

The present invention relates to telephone sets for communication in airplanes, and more particularly to an improved casing for receivers used in connection with aviators' helmets and is directed generically to the same subject matter as is disclosed in the copending application of Gerald Klein, Serial No. 150,429, filed June 26, 1937.

It is known to provide telephone receivers with a casing which encloses the ear and seals it against extraneous noises which might interfere with a clear understanding. It further has been proposed to lessen the pressure which such enclosed receivers exert on the ear by employing intermediate rubber cushions or the like.

According to the invention, a telephone receiver is enclosed by an outer shell-like casing and by an inner cover which surrounds the ear of the wearer and is so dimensioned that the ear may freely lie therein. The cover has the shape of a cup or pot whose bottom is provided with one or more openings for the passage of the sound and lies directly in front of the telephone system. The cover consists preferably of leather.

In the accompanying drawing is shown an embodiment of the invention in a sectional view. In this figure, 5 represents the outer portion of an aviator's helmet or of a similar attachment, 7 the inner portion thereof consisting of a lining of yielding material, and 3 a telephone receiver system. A casing 1 covering the receiver is secured to the helmet 5 by means of a spring ring 6. The casing has preferably the form of an oval shell, in the central circular flange 2 of which are fitted the telephone system 3 and the diaphragm with the cover 4. The lining 7 covering the inner side of the helmet 5 extends only to the edge of the casing 1, so that the opening of the casing remains free. This opening is closed by a pot-shaped cover 8 of leather or similar absorbing material. The cover 8 is firmly secured between the lining 7 and the helmet 5 as shown in the drawing and the bottom thereof lies directly in front of the telephone system 3, from which pass the sound waves to the ear of the user through an opening 9 arranged in the bottom of the cover 8. As will be seen the cover is so dimensioned that the ear with the helmet on the head of the user is completely enclosed by the cover and lies freely therein. Thereby the ear is sealed against any noises which might interfere with a clear under-

standing without a pressure being exerted on the ear.

The shape of the casing 1 as well as the arrangement of the receiver may be different from that shown and described. Also the cover 8 may have another shape.

What is claimed is:

1. In combination, an aviator's helmet having an opening therein, a telephone receiver, holding means for said receiver acoustically sealing one side thereof, means attaching said holding means to said helmet, a cup-shaped member, an opening in the bottom of said member aligned with said receiver and means attaching the rim of said member to said helmet with the open end of said member facing the interior of said helmet and the cup-shaped part exteriorly of said helmet whereby a receptacle is formed for the ear of the aviator surrounding the same and separated therefrom.

2. In combination, an aviator's helmet, a lining therein, said helmet and lining having an opening therein, a cup-shaped member having a flange at the open end thereof, said cup-shaped member extending exteriorly of said helmet, means holding said flange between said lining and helmet, a casing, a receiver, means in said casing holding said receiver whereby said receiver is acoustically shielded at one side thereof, and means attaching said casing to said helmet with the other side of said receiver adjacent said cup-shaped member, said member having an opening aligned with said receiver.

3. In combination, a helmet member having an ear opening therein, a pair of internested members attached to said helmet, the inner member being shaped to provide an ear receptacle surrounding and separated from the ear of a wearer of said helmet and a receiver held between said internested members, said inner member having an opening therein.

4. In combination, a helmet member, having an ear opening therein, a pair of internested members located in said opening, the inner of said members comprising a perforated flexible receptacle surrounding and separated from the ear of the wearer of said helmet, and a receiver between said members, said outer member acoustically sealing said receiver to said helmet.
